UNITED STATES PATENT OFFICE

LAURICE L. LOCKROW, OF BROOKLYN, NEW YORK, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed February 7, 1927, Serial No. 166,395. Renewed July 3, 1929.

My invention relates to railway traffic controlling apparatus, and particularly to apparatus of the type comprising means for supplying the trackway with alternating current which is periodically varied at different frequencies, and governing means on the train selectively responsive to the frequency of such variations.

I will describe two forms of railway traffic controlling apparatus embodying my invention, and will then point out the novel features thereof in claims.

In the accompanying drawings, Fig. 1 is a diagrammatic view illustrating one form of railway traffic controlling apparatus embodying my invention. Fig. 2 is a view showing a modified form of the train carried portion of the apparatus illustrated in Fig. 1 and also embodying my invention.

Similar reference characters refer to similar parts in both views.

Referring first to Fig. 1, the reference characters 1 and 1^a designate the track rails of a stretch of railway track over which traffic normally moves in the direction indicated by the arrow. These rails are divided, by means of insulated joints 2, into a plurality of successive track sections only one of which, A—B, is shown complete in the drawing. Train controlling current is supplied to the rails of each section from a suitable source of energy such as an alternator G. The current supplied to the track rails by this alternator may be of a frequency of the order of the usual commercial alternating current such for example as 60 cycles or 100 cycles per second.

The supply of current to the trackway is controlled by a coding device designated in general by the reference character X and comprising a plurality of rotatable cams each designated by the reference character C with a suitable distinguishing exponent. The cams C are driven at a constant speed by a suitable motor M which is supplied with current from the alternator G. The cam C¹ is provided with a plurality of swells 8 spaced about its periphery and which swells successively engage a contact 3 to periodically close the contact as the cam C¹ is ro-

tated. In similar manner the cams C² and C³ are provided with different numbers of swells 8 which control contacts 4 and 5, respectively. One terminal of the alternator G is constantly connected with rail 1 of section A—B, and the other terminal of the alternator is connected with the rail 1^a through one of the contacts 3, 4 or 5, depending upon traffic conditions.

It is manifest that the alternating current supplied to the rails of the trackway by alternator G is periodically varied at the frequency of operation of the contact of the device X that is interposed between the alternator and the track rail 1^a. The coding device X may be constructed to provide variations of any reasonable frequencies, but for purposes of illustration, I will assume that the cams C are rotating at 20 revolutions per minute, that cam C¹ has 4 swells, that cam C² has 6 swells, and that cam C³ has 9 swells. The selection between the several contacts of the coding device X in accordance with traffic conditions may be accomplished in any suitable manner, such, for example, as by means of a home relay H and a distant relay L. The circuits for controlling these two relays form no part of my present invention and are omitted from the drawing for the sake of simplicity. For present purposes it is sufficient to state that home relay H is normally energized but is de-energized when a train occupies the section immediately to the right of point B. The distant relay L is also normally energized but is de-energized when a train occupies either the first or the second section immediately to the right of point B. With the apparatus thus far described, when relays H and L are both energized so that front contact 6—6^a of relay H and front contact 7—7^a of relay L are closed, current from alternator G, which current I will assume to be of 100 cycles per second, is supplied to the track rails over contact 5 operated by cam C³. Under these conditions the alternating current supplied to the trackway is periodically varied at a frequency of 180 cycles per minute. Current supplied to the trackway under these conditions, I will hereinafter term the "proceed

85

90

95

100

code". When relay H is energized and when relay L is de-energized, so that front contact 6-6^a of relay H and back contact 7-7^b of relay L are closed, contact 4 controlled by cam C² is included in the trackway circuit and under these conditions the trackway is supplied with 100-cycle current interrupted at a frequency of 120 cycles per minute; this current I shall hereinafter term the "caution code". In similar manner when relay H is de-energized, the closing of back contact 6-6^b of this relay completes a circuit from alternator G to the track rails through contact 3 operated by cam C¹. Under these conditions the trackway is supplied with 100 cycle current interrupted at a frequency of 80 cycles per minute, which current I will call the "slow code".

The train indicated diagrammatically at 20 V is provided with governing means which is selectively responsive to the frequency of the periodic variations in the 100 cycle current supplied to the trackway. In the present embodiment of my invention the train is provided with two magnetizable cores 11 and 11^a located in advance of the forward axle 10 and disposed in inductive relation to the two track rails 1 and 1^a, respectively. Core 11 is provided with a winding 12, and core 30 11^a is provided with a winding 12^a, the two windings 12 and 12^a being connected in series in such manner that the voltages induced therein by alternating currents flowing in opposite directions in the track rails at an instant are additive. Windings 12 and 12^a are connected through an amplifier 13 with the primary of a transformer Q the secondary of which supplies energy to a polarized relay R. When train controlling current is being supplied to the trackway, pulsating energy is delivered to the primary of transformer Q at the frequency of the periodic variations in such trackway current. For each impulse of energy supplied to transformer Q, during 40 the increase of such current, an impulse of one relative polarity is supplied to relay R and during the decrease of such current, an impulse of the opposite relative polarity is supplied to the relay. The relay R is responsive to the relative polarity of the current supplied thereto, and it follows that when the train controlling current supplied to the trackway is being periodically varied, the relay R is operated to swing its armature 45 alternately to the right and left at a frequency which corresponds to the frequency of the variations of the trackway current.

The relay R controls the supply of direct current from a suitable source such as a battery D to the primary 27 of a transformer T¹. When armature 15 of relay R occupies its left-hand position to close contact 15-18^a, current from battery D flows through the lower half of primary 27 of transformer T¹ in one direction, the circuit being from bat-

tery D through contact 15-18^a, wire 50, lower half of primary 27, and wires 51 and 52 to battery D. When the armature 15 of relay R occupies its right-hand position to close contact 15-18^b, current from battery D flows through the upper half of primary 27 in the opposite direction, the circuit being from battery D through contact 15-18^b, wire 53, upper half of primary 27, and wires 51 and 52 to battery D. It follows that when one of the codes is being supplied to the relay R to operate the relay, the current supplied to the primary of transformer T¹ is periodically reversed. As a result there is induced in the secondary 28 of transformer T¹, an alternating electromotive force which operates a relay K¹ through a rectifier J¹. Relay K¹ is therefore continuously energized when the current supplied to the trackway is being periodically varied in accordance with one of the codes, but this relay is de-energized under all other conditions.

The selection between the several codes is accomplished by means of two oscillators F² and F³ controlled by the relay R and tuned to mechanical resonance at different frequencies. Referring particularly to oscillator F³, the reference characters 19 and 20 designate two electromagnets which are arranged, when energized, to swing a pivoted armature 21 in opposite directions. When contact 15-16^a of relay R is closed, magnet 19 is energized to swing armature 21 in a clockwise direction, the circuit being from battery D through contact 15-16^a, wire 54, magnet 19, and wires 51 and 52 to battery D. When contact 15-16^b of relay R is closed, however, magnet 20 is energized to swing armature 21 in the opposite direction, the circuit being from battery D through contact 15-16^b, wire 55, magnet 20, and wires 51 and 52 to battery D. When one of the codes is being supplied to the trackway, therefore, the armature 21 oscillates to and fro at the frequency of operation of relay R. The oscillator F³ also comprises a bar 22 carried by a shaft 23 which as here shown is perpendicular to the plane of the paper. The bar 22 is biased by springs 38 and 39 to a definite position. The bar is also connected by two other springs 36 and 37 with the armature 21. By means of suitable weights 22^a on the bar 22 the moving parts of the oscillator are tuned to mechanical resonance at the frequency of one of the codes. I will assume that oscillator F³ is tuned to resonance at 180 cycles per minute. Under some conditions it may be desirable to provide a brush 24 bearing on the shaft 23 of the oscillator to introduce a small amount of friction for the purpose of damping the moving parts and thereby increasing the width of the band of frequencies to which the oscillator will give a resonant response. It will be plain from the foregoing explanation that since the oscillator F³ is tuned to mechanical resonance 125 130

at a frequency of 180 cycles per minute, the bar 22 will be swung to and fro by oscillation of the armature 21 when and only when the armature oscillates at the frequency to which the oscillator is mechanically tuned. The shaft 23 operates a contact mechanism comprising a finger 25 and two fixed contacts 25^a and 25^b. When the oscillator is being operated at its resonant frequency the contacts 25—25^a and 25—25^b are alternately closed due to the oscillation of the bar 22. Each time one of these contacts is closed an impulse of energy is delivered from a battery P² to the primary 27 of a transformer T². The pulsating current thus supplied to the primary 27 induces an electromotive force in secondary 28 which energizes a relay K² through a rectifier J². Relay K² is energized, therefore, when and only when current is supplied to the trackway in accordance with the proceed code. The oscillator F² is similar to oscillator F³ except that F² is tuned to mechanical resonance at 120 cycles per minute. The circuit for magnet 19 of oscillator F² is from battery D through contact 15—17^a of relay R, wire 56, magnet 19, and wires 51 and 52 to battery D. The circuit for magnet 20 of this oscillator is from battery D through contact 15—17^b, wire 57, magnet 20, and wires 51 and 52 to battery D. When the relay R is operating at 120 cycles per minute, the oscillator F² closes its contacts 25—25^a and 25—25^b alternately, thereby periodically closing the circuit including primary 27 of transformer T² and battery P². The electromotive force thus induced in secondary 28 of transformer T² operates a relay K² through a rectifier J².

It will be clear from the foregoing that oscillator F³ will not operate to close its contacts 25—25^a—25^b except upon the delivery to its magnets 19 and 20 of impulses according to the proceed code, and that oscillator F² will not operate to close its contacts except upon delivery to its magnets 19 and 20 of impulses according to the caution code.

In explaining the operation of the apparatus as a whole, I will first assume that relays H and L are both energized so that current is being supplied to the trackway, over contact 5 operated by cam C², in accordance with the proceed code. Relay R therefore operates at 180 cycles per minute and oscillator F³ is operated to energize relay K³, but oscillator F² does not effectively operate and relay K² is open. Relay K¹ is energized and current flows from a suitable source of energy such as a battery S over front contact 33—33^a of relay K¹, back contact 34—34^b of relay K², front contact 35—35^a of relay K³ to lamp 29, thereby lighting this lamp to display a proceed indication on board the train.

I will next assume that relay L is de-energized, but that relay H is energized so that current is supplied to the rails of section

A—B in accordance with the caution code. Relay R therefore operates at a frequency of 120 cycles per minute. Under these conditions the oscillator F² operates to energize relay K² but the oscillator F³ is de-tuned at the frequency of the caution code, so that the amplitude of vibration of bar 22 of oscillator F³ is not sufficient to effectively operate the contact mechanism controlled by this oscillator and relay K³ is de-energized. Relay K¹ is energized, however, and current flows from battery S, over front contact 33—33^a of relay K¹, front contact 34—34^a of relay K² and lamp 30, thereby lighting this lamp to give a caution indication.

When the trackway is being supplied with current in accordance with the slow code, as when relay H is de-energized, relay R operates at 80 cycles per minute. Under these conditions, relay K¹ is energized but oscillators F² and F³ are both de-tuned at this frequency and the contact mechanisms controlled by the oscillators are not effectively operated so that relays K² and K³ are both de-energized. Current from battery S therefore flows over front contact 33—33^a of relay K¹, back contact 34—34^b of relay K², back contact 35—35^b of relay K³ to lamp 31, thereby lighting this lamp to give a slow indication.

If section A—B were occupied by a second train located between train V and point B, train controlling current would be shunted away from train V by the wheels and axles of such second train. As a result relay R would be continuously de-energized. If, for this reason, or for any other reason, relay R should fail to operate intermittently the supply of periodic current to the primary of transformer T¹ would be interrupted and relay K¹ would be de-energized. Under these conditions current from battery S would flow over back contact 33—33^b of relay K¹ to light lamp 32 and display a stop indication on board the train.

In the modified form of apparatus shown in Fig. 2, the relay R is arranged to operate at the frequency of the train controlling code as in Fig. 1. In Fig. 2, however, the relay R controls three oscillators F¹, F² and F³ each tuned to mechanical resonance at the frequency of one of the codes. In the form here shown each of the oscillators comprises two magnets 19 and 20 which control an armature 21 pivotally supported by a polarized back strap 36. The armature 21 carries a tongue 37 which is mechanically tuned, as by a weight 38, and which tongue co-operates with two fixed contacts 37^a and 37^b. The contacts 37—37^a and 37—37^b of each oscillator F control the supply of current from an associated battery P to the primary 27 of an associated transformer T. The secondary 28 of each transformer T supplies energy to a relay K through a rectifier J. The oscil-

lator F^1 is tuned to mechanical resonance at 80 cycles per minute, oscillator F^2 is tuned to mechanical resonance at 120 cycles per minute and the oscillator F^3 is resonant at 180 cycles per minute. It follows therefore that when current is being supplied to the trackway in accordance with one of the codes, the oscillator which is tuned to resonance at a corresponding frequency operates but the remaining two oscillators do not operate effectively. For example, when the proceed code is being supplied to the trackway the oscillator F^3 operates to energize relay K^3 but the oscillators F^1 and F^2 will not effectively operate at this frequency and relays K^1 and K^2 are both de-energized. Under these conditions, current flows from battery S, over front contact 35—35^a of relay K^3 to the proceed lamp 29. When the caution code is being received from the trackway, the oscillator F^2 operates to energize relay K^2 but relays K^3 and K^1 are both de-energized. Under these conditions the caution lamp 30 is lighted by current from battery S over back contact 35—35^b of relay K^3 and front contact 34—34^a of relay K^2 . Similarly, when the slow code is being supplied to the trackway, the oscillator F^1 operates and relay K^1 is energized, but relays K^2 and K^3 are both de-energized, and the slow lamp 31 is lighted by current which flows from battery S, over back contact 35—35^b of relay K^3 , back contact 34—34^b of relay K^2 and front contact 33—33^a of relay K^1 . If relays K^1 , K^2 and K^3 are all de-energized to close their back contacts, lamp 32 is lighted to indicate stop. In both forms of apparatus which I have here disclosed, the selection between different code frequencies is accomplished by mechanical tuning, although my invention is not limited to this specific type of tuning but is broad enough to include apparatus tuned or made resonant in any suitable manner as a means for selecting between the different code frequencies. Among the advantages possessed by apparatus constructed in the manner described are the simplicity and ruggedness with which the various parts may be constructed and the freedom of the tuned devices from improper operation due to mechanical vibration. The sharpness of the tuning may be adjusted within comparatively wide limits by varying the amount of damping of the movable members of the oscillators.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. Railway traffic controlling apparatus

comprising means for supplying alternating current to the trackway, means for periodically varying such current at different frequencies, and resonant means on the train selectively responsive to the variations in such current but not to the current itself. 70

2. Railway traffic controlling apparatus comprising means for supplying alternating current to the trackway, means for periodically varying such current at different frequencies, and a plurality of train carried devices all controlled by energy received from the trackway and each tuned to resonance at a different one of such frequencies. 75

3. Railway traffic controlling apparatus comprising means for supplying alternating current to the trackway, means for periodically varying such current at different frequencies, and a plurality of devices controlled by energy received from the trackway and responsive to variations in such current but not to the current itself, said devices being tuned mechanically to the several frequencies of such variations. 80

4. In combination, a source of alternating current, means for periodically varying the current at different frequencies, and a plurality of devices all controlled by energy from such source and each tuned to a different one of the frequencies of such variation. 90

5. Railway traffic controlling apparatus comprising means for supplying alternating current to the trackway, means for periodically varying such current at different frequencies, a plurality of oscillators each controlled by energy received from the trackway and each tuned to resonance at a different one of such frequencies, and train carried governing means selectively controlled by the oscillators. 100

6. Railway traffic controlling apparatus comprising means for supplying alternating current to the trackway, means for periodically varying such current at different frequencies, and a plurality of train carried oscillators all receiving energy according to the variations in such current and each tuned to resonance at a different one of the frequencies of such variations. 105

7. Railway traffic controlling apparatus comprising means for supplying alternating current to the trackway, means for periodically varying such current at different frequencies, a plurality of train carried oscillators each tuned to mechanical resonance at one of such frequencies, and means for supplying energy to all such oscillators in accordance with the variations in said current. 115

8. In combination, a pair of conductors supplied with alternating current of commercial frequency, means for periodically varying such current at different frequencies of the order of 80 to 180 cycles per minute, and a plurality of devices receiving energy from such conductors and each tuned 125

to resonance at a different one of such latter frequencies.

9. In combination, a source of periodic currents of different frequencies of the order of 80 to 180 cycles per minute, a plurality of devices all receiving energy from said source and each tuned to resonance at a different one of such frequencies, and governing means selectively controlled by such devices.

10. Railway traffic controlling apparatus comprising means for supplying the track-way with alternating current of commercial frequency periodically varied at different frequencies of the order of 80 to 180 cycles per minute, a plurality of train carried oscillators each tuned to mechanical resonance at a different one of such latter frequencies, means for supplying all said oscillators with energy in accordance with said variations, and governing means selectively controlled by the oscillators.

11. Railway traffic controlling apparatus comprising means for supplying the track-way with alternating current periodically varied at different frequencies, a train carried relay responsive to such variations but not to the current itself, and a plurality of oscillators all controlled by such relay and each tuned to mechanical resonance at one of such frequencies.

12. Railway traffic controlling apparatus comprising means for supplying the track-way with alternating current periodically varied at different frequencies, a train carried relay responsive to such variations but not to the current itself, a governing device on the train controlled by the relay and responsive to such variations, a plurality of oscillators all controlled by such relay and each tuned to mechanical resonance at a different one of such frequencies, and a plurality of other governing devices selectively controlled by such oscillators.

13. In combination, a source of alternating current, means for periodically varying the current from said source at different frequencies, a relay receiving energy from the source and responsive to such variations but not to the current itself, a plurality of oscillators controlled by the relay and each comprising a movable member tuned to mechanical resonance at a different one of such frequencies, a contact mechanism controlled by each such member, and governing means selectively controlled by said contact mechanisms.

14. In combination, a relay, means for operating the relay at different frequencies, a plurality of oscillators controlled by said relay and each comprising a member tuned to mechanical resonance at a different one of such frequencies, and governing means selectively controlled by the oscillators.

15. Railway traffic controlling apparatus comprising means for supplying alternating

current to the track rails, means for periodically varying such current at different frequencies, a train carried relay responsive to such variations but not to the current itself, a plurality of oscillators each comprising a member tuned to resonance at a different one of such frequencies and a pair of electro-magnets arranged to move the member in opposite directions, means controlled by the relay for alternately energizing the electro-magnets of each oscillator at the frequency of such variations, and governing means selectively controlled by such oscillators in accordance with the frequency of such variations.

16. Railway traffic controlling apparatus comprising means for supplying alternating current to the track rails, means for periodically varying such current at different frequencies, a train carried relay responsive to such variations but not to the current itself, a plurality of oscillators each comprising a pair of electro-magnets and a polarized back strap, an armature supported by each back strap and urged in opposite directions by the associated electro-magnets, each such armature being tuned to resonance at one of such frequencies, means controlled by the relay for alternately energizing the electro-magnets of each oscillator at the frequency of such variations, and governing means selectively controlled by such oscillators in accordance with the frequency of such variations.

In testimony whereof I affix my signature.
